UNITED STATES PATENT OFFICE.

ALICE PFLIEGER, OF COLUMBUS, OHIO.

DESIGN FOR A CURLING-IRON HOLDER.

SPECIFICATION forming part of Design No. 29,230, dated August 16, 1898.

Application filed July 18, 1898. Serial No. 686,306. Term of patent 7 years.

To all whom it may concern:

Be it known that I, ALICE PFLIEGER, a citizen of the United States, residing at Columbus, in the county of Franklin and State of 5 Ohio, have invented and produced a new and original Design for a Holder for Heating Curling-Irons; and I do hereby declare the following to be a full, clear, and exact description of the same, reference being had to the accompanying drawing, forming a part thereof.

In the drawing the view illustrates an embodiment of my design in perspective.

As indicated in said drawing, the holder is formed of wire bent and folded at intervals 15 to form arms 1, radiating in the same plane from a central frame 2. At the junction of the arms 1 with the central frame 2 the wires composing the arms 1 are shown to be twisted

for a short distance, while the outer extremities of the arms are all bent downward to 20 form legs standing at an angle to the plane of the portions 1, as shown at 1^a.

The leading feature of my design is the curling-iron holder of wire bent to form the arms and legs, with common central portion 25 or frame 2.

What I claim, and desire to secure by Letters Patent, is—

The design for a curling-iron holder, substantially as herein shown and described. 30

In testimony whereof I affix my signature in presence of two witnesses.

ALICE PFLIEGER.

Witnesses:
